UNITED STATES PATENT OFFICE.

EDWIN F. GUTH, OF ST. LOUIS, MISSOURI.

BOWL-SUPPORTING MEANS FOR LIGHTING FIXTURES.

Application filed October 10, 1925. Serial No. 61,637.

My invention relates to the art of illumination, and particularly to means for supporting bowls used in connection with fixtures, principally electrically operated fixtures, and has for its object to produce such a means in a simple, strong, durable, and practically inexpensive, construction, which may be easily and quickly operated to secure the bowl to, or release it from, the fixture.

10 A further object is to produce such a means as will be practically concealed from view, and will not detract from the graceful, symmetrical, and beautifying, character of the fixture.

15 My invention consists of the details of construction hereinafter set forth, pointed out in my claims, and illustrated in the accompanying drawings, in which

Fig. I shows a side elevation view of a fixture equipped with my improved bowl-supporting means;

Fig. II shows a vertical sectional view, taken on the line 2—2 of Fig. I;

Fig. III shows a detail view of my supporting rod or wire; and

Fig. IV shows a detail view of a fragment of a bowl, disclosing the recess formation I place therein.

Referring to the accompanying drawings, 30 the reference numeral 10 is used to indicate a bowl designed to be secured to a lighting fixture, 11 the lamp bulb, 12 the cone, or shell, surrounding the socket which supports the lamp, 13 the reflector which is sometimes used in lighting fixtures, and 14 the rod, or wire, supports, by means of which the bowl 10 is secured to the fixture. These supports, 14, and their novel formation, together with the recess formations in the bowl, and the slot and orifice, or recess, formation in the cone, constitute my invention.

The bowl 10, which is preferably formed of glass, is provided with two, or more, 45 grooves, slots or recesses, 15, pressed into the upper portion (commonly called the lip), the base of said groove 15 having a relatively sharp angle at its outer extremity. Obviously, these grooves are evenly spaced and arranged around the bowl, and when only two are used they are spaced at directly opposite points in the lip of the bowl.

50 The support 14 is, preferably, formed of a stiff strand of wire, and a hook, 16, is formed at its base, and this hook is off-set at a desirable angle from the main body portion

of the support. In advance of the hook 16 I have formed a depending shoulder 17, the inturned end of the hook and the end of the shoulder being designed to be on a substantially horizontal plane in relation to each other when the support is functioning to secure the bowl to the fixture. The hook end and shoulder of the support 14 are designed to be received by, and countersunk in, the groove 15.

The upper end of the support 14 also terminates in a hook, 18, which enters cone 12 through a slot, or orifice, 19, of substantially the same width as the wire 14, and is anchored in an orifice, 20, directly below, and in a vertical plane with, the orifice 19.

The grooves 15 in the bowl 10 function to keep the supporting wires 14 in proper, and permanent, spaced relation around the bowl, 75 and, as will be hereinafter explained, to form walls extending upwardly from the lip to which the hook 16 is clamped when the support is drawn toward the center for attaching to the fixture. Also, the grooves 80 provide for practically concealing the supporting wires from view, so as not to mar the appearance of the regular upper surface of the bowl.

In practical operation, the lower hook 16 85 is placed in its groove 15, the inturned end of the hook seating itself below the material forming the base of the groove. The support 14 is then moved inwardly from this seating until the shoulder 17 abuts 90 against the material forming the base of the groove (but on the upper side thereof). The walls of the groove (the hook being, as stated, countersunk in the groove), serve to anchor the support, firmly, against side- 95 wise movement.

The hook 18 is inserted through the slot 19 in the cone 12, then drops downwardly, its inturned end entering, and being anchored in, the orifice 20. As the orifices 19 100 and 20 are in a substantially vertical line, and are each of only such diameter as to permit the hook to pass therethrough, it is apparent the support 14 must remain in a vertical position in one direction though 105 extending outwardly from the cone to the bowl to which it is secured, as described. This construction supports the bowl in a true horizontal plane and functions perfectly for that purpose, even though only two 110 supports may be employed.

It is not necessary that the groove 15 ex-

tend entirely through the lip of the bowl, although I have chosen this means of illustration. It would be sufficient if a groove, or slot, were formed in the bowl to receive the hook 16, in such manner that the in-turned end of the hook would engage and overlap material in the bowl, and an angle in the base of the groove be formed to receive the shoulder 17, the construction being such that when the shoulder is engaging the material of the bowl, the in-turned end of the hook is firmly seated below material forming the base of the slot.

It is also not essential to have orifices in the cone, as the formation of a recess in the cone to receive the hook member 18, and to firmly anchor it to the cone, would be sufficient, if the groove were so formed, and would so receive the hook member 18, as to provide against lateral movement of the support 14, and thus hold the support in a true vertical position.

The principal function of the recesses and grooves in the bowl, and in the cone, in addition to providing anchoring means for their respective hooks, is to provide walls, spaced just sufficiently to receive the supporting hooks, thereby causing these walls to function to provide against lateral movement of the support, when the support has been placed therein, thereby insuring the true horizontal positioning of the bowl with relation to the fixture.

Having thus described my invention, what I claim and desire to secure by Letters Patent of the United States is:

1. A bowl supporting means for lighting fixtures, comprising a plurality of supporting members formed with hooks on each end; a shoulder on the lower hook, faced toward the in-turned end of the hook; grooves in the bowl to receive the lower hooked members of the supports; means to attach the upper hooks to the fixture.

2. A bowl supporting means for lighting fixtures, comprising a plurality of support members formed with hooks on each end; a shoulder on the lower hook, faced toward the in-turned end of the hook; grooves in the bowl to receive the lower hooked members of the supports; means to attach the upper hooks to the fixture, this means providing against lateral movement of the support.

3. A supporting means for bowls for lighting fixtures, comprising recesses formed in the bowl in its upper surface, there being spaced walls to such recesses; means in said recesses to receive a hook; a support with a hook formed on each end thereof, the lower hook being designed to enter one of said recesses in the bowl; a shoulder on the support, facing the in-turned end of the hook, and so arranged as to engage the material in the bowl when the hook is seated in the recess; a hook on the upper end of the support; means to secure the upper hook to the lighting fixture.

4. A supporting means for bowls for lighting fixtures, comprising recesses formed in the bowl in its upper surface, there being spaced walls to such recesses; means in said recesses to receive a hook; a support with a hook formed on each end thereof, the lower hook being designed to enter one of said recesses in the bowl; a shoulder on the support, facing the in-turned end of the lower hook, and so arranged as to engage the material in the bowl when the hook is seated in the recess; a hook on the upper end of the support; means to secure the upper hook to the lighting fixture, said means providing against lateral movement of the support when the hook has been seated in the fixture.

5. A bowl supporting means for lighting fixtures, comprising recesses formed in the bowl in its lip, said recesses being formed with spaced walls, and adapted to receive and anchor a supporting member; means to secure supporting members in said recesses, and means to attach the opposite ends of the supporting members to the lighting fixture, substantially as shown and described.

6. A bowl supporting means for lighting fixtures, comprising recesses formed in the bowl evenly spaced and arranged around the lip of the bowl, said recesses being formed with spaced walls, and adapted to receive and anchor a supporting member; means to secure supporting members in said recesses, and means to attach the opposite ends of the supporting members to the lighting fixture, substantially as shown and described.

EDWIN F. GUTH.
